RAT GUARD FOR SHIPS

Walter M. Mullins, Costa Mesa, Calif.

Application September 18, 1948, Serial No. 49,888

14 Claims. (Cl. 114—221)

1

The application refers to rat guards which are customarily used on mooring lines by which ships are moored to some shore installation.

Rats have been a common pest to shipping for a great many years, and it is common knowledge that rats are prone to board ships by running along the mooring lines and harboring themselves in the ship until the ship docks at some new port when the same rats will use the mooring line as a vehicle for going ashore. Rats 10 picked up by ships in foreign lands are often carriers of disease to our shores and various means have been employed in the past for preventing the importation of these mammals. Rats are otherwise undesirable inhabitants of ships, and it is the desire at all times to keep ships as free from rats as possible.

Heretofore rat guards of a specific type have been almost universally used. These rat guards consist of a somewhat circular disc having a hole through the center approximately equal to the diameter of the mooring line, the disc being split so that it can be applied over the line. It has been necessary also to secure the disc in proper position some distance out from the ship to prevent rats from jumping from the line to some portion or other of the ship. For anchoring the discs, they have been provided with projections extending laterally from the disc in positions lying adjacent the mooring line, and common practice has been to tie the projections to the line.

Although these discs are particularly effective in preventing rats from boarding ships when properly affixed to the mooring line, the difficulty arises when the discs are not properly attached or perhaps not attached at all. Modern ships ride very high above the water, sometimes twenty or thirty feet. The discs to be effective must be anchored to the line some three feet or more from any projection on the ship. This means that a sailor must stretch out from the ship hanging twenty or thirty feet above the water and in the precarious position tie the disc in place. Because of the carelessness of sailors on occasions, the discs are not properly attached and slide down the mooring line to ineffective positions. Sometimes the discs are not attached far enough away from the ship to prevent rats from jumping from the line to the ship.

In addition to these defects, the same discs must be removed from the line when the ship is ready to sail in order that the line may be hauled aboard. To untie the disc from the line presents the same difficulties as when the discs are

2

affixed to the line and very frequently the discs are damaged when the mooring line is hauled aboard.

It is, therefore, among the objects of the invention to provide a new and improved rat guard for mooring lines, which is adapted to attach itself automatically to the line when dropped upon the line at any given distance from the ship and there anchor itself in place.

Another object of the invention is to provide a new and improved rat guard for mooring lines which can be readily lifted from its attached position on the line by merely drawing in upon a tie rope which extends from the rat guard to the ship.

Still another object of the invention is to provide a new and improved rat guard for mooring lines which includes a combined baffle and gravity actuated latch adapted to be adjusted to lines of different diameter.

A still further object of the invention is to provide a new and improved rat guard which is capable of remaining in its properly adjusted position without being easily disturbed, which is easy to apply and remove, and which at the same time is simple in its structure, inexpensive in its manufacture and particularly effective in preventing rats of all sizes from running from one end of the line to the other.

With these and other objects in view, the invention consists in the construction, arrangement and combination of the various parts of the device whereby the objects contemplated are attained, as hereinafter set forth, pointed out in the appended claims, and illustrated in the accompanying drawings.

In the drawings:

Figure 1 is a perspective view showing the rat guard in position on a mooring line attached to a wharf.

Figure 2 is an end view of the rat guard drawn to a larger scale showing the position of the parts when the guard is attached to a line.

Figure 3 is a fragmentary cross-sectional view of that portion of the guard adjacent the mooring line taken on the line 3—3 of Figure 1.

Figure 4 is a fragmentary side elevational view taken on the line 4—4 of Figure 3.

Figure 5 is a vertical sectional view of a modified form of the device showing the device in extended position on a mooring line.

Figure 6 is a side elevational view of the device in collapsed condition.

Figure 7 is a cross-sectional view of the device on the line 7—7 of Figure 5.

Figure 8 is a fragmentary cross-sectional view taken on the line 3—8 of Figure 5.

In the embodiment chosen to illustrate the device, the rat guard is shown as comprising a housing adapted to ride upon the line in any position at which it may be attached, whether the line be substantially horizontal or whether it be tilted at a considerable angle. The housing is shown as one constructed in the form of a block or shield 10 having high steeply slanting walls 11 and 12 terminating in a ridge or peak 13 at the top. A ring 14 extends through the block near the top to which may be attached a tie rope 15 used when dropping the guard upon the line when it is attached and in pulling the guard back to the ship when it is removed.

At the bottom of the block are skirts 16 and 17, the top edges of which lie along the bottoms of the walls 11 and 12. These skirts are likewise designed to overlie the sides of a mooring line 18. The front and rear of the block are disclosed by vertical triangular walls 19.

An examination of Figure 2 will reveal that the lower portion of the block adjacent the junction of the block with the skirts forms a tunnel 20, the roof of which comprises sheet metal members 21 and 22, so that the entire block or housing is closed in except for the tunnel formed by the skirts.

For holding the block or housing in a proper upright position on the line, there is provided a counter-balance consisting in the embodiment illustrated of a continuous rod 23 having an upper horizontal portion 24 extending transversely through the block at a location above the tunnel, the rod being permitted to swing freely upon the upper portion 24. Washers 25 may be affixed to the rod to anchor it properly in place. The rod also includes downwardly extending portions 26 spaced some distance laterally with respect to the skirts and terminating in weight members 27 at the bottom.

For affixing the housing to the line, there is provided what may be termed a secondary shield here shown in the form of a plate 30 which is adapted to extend transversely from one skirt to another approximately midway between the ends of the skirts. In this embodiment the skirts are provided with aligned slots 31 which are adapted to receive the plate. As readily apparent in the drawing, an upper edge 32 of the plate is provided with a recess 33 of one diameter adapted to fit the line 18 herein illustrated and an opposite edge 34 provided with a recess 35 of larger diameter adapted to fit a mooring line of corresponding diameter.

For mounting the plate upon the block or more particularly, one of the skirts, there is provided a rod or shaft 36 which serves a multiple purpose. The rod or shaft includes a portion 37 which extends across the face of the plate 30 and is adapted to be secured within a pressed-out portion 38 on the plate, sized to fit around it. A spring retaining washer 39 is attached to the end of the portion 37 and a spring 40 is retained under compression by the washer 39. At the end of the pressed-out portion 38 opposite from the spring there is provided a transverse slot indicated generally by the reference character 42 which has an upper portion 42' and a lower portion 42''. These portions have open right-hand ends as viewed in Figures 2 and 3 and are merely slots cut out of the pressed-out portion 38. A pin 41 is set transversely in the portion 37 of the rod 36 at a location such that it can

fall into either the portion 42' or the portion 42'' of the slot. In Figures 2 and 3 the pin is held by action of the spring 40 in the upper of the two portions, namely, the portion 42'. The plate 30, however, can be reversed by pushing it laterally so as to compress the spring 40 sufficient to let the pin 41 ride out of the portion 42' at which time the plate can be reversed until the pin is in a position to fall into the portion 42'' wherein it will be retained by action of the spring 40.

The shaft 36 includes a second portion 43 lying normally parallel to the plate 30 and this portion 43 has mounted thereon a cross-pin 44 which, in turn, is secured by brackets or bearings 45 to the skirt 16. The pin 44 is adapted to provide a pivotal mounting for the rod portion 43 upon the skirt so that the plate may be swung from the solid line position, shown in Figure 2, outwardly to the dot-and-dash line position thereshown and, in fact, further outwardly, in order to permit the housing to be applied to and removed from the mooring line. In its outermost position also the plate may be rotated about the portion 37 end for end so that either the recess 33 or the recess 35 may be applied to a position adjoining the line. At one end of the plate, there is provided a slot 46 adapted to fit over the pin 44 in one position of adjustment of the plate. Because of the difference in diameter of the lines which the plate is adapted to fit, the location of the portion 37 of the rod is nearer the recess 35 than the recess 33 which necessitates the provision of the slot 46 in order to accommodate itself to a proper position of adjustment.

Also on the rod 36 there is provided an extension 50 curved to improve smoothness of operation, which extends to a position part-way over the recess 33 or the recess 35 should that recess be in a position for application to the line. The extension 50 is the means for manipulating the plate so that the plate and the rod by which it is used may serve as a latch for securing the housing to the line.

In operation the line 18 is ordinarily extended from the ship to a pile 51 on a wharf 52. After the line is secured, the rat guard is mounted in position. Before it is applied, the plate 30 is tilted outwardly to the dot-and-dash line position, illustrated in Figure 2, which position the plate will hold because of the balance of the plate about the pin 44. The housing is then held above the line at whatever location it is desired to attach the housing and then dropped upon the line. The weight of the housing pressing downwardly upon the pin 44 where it is pivotally connected to the rod 43 is sufficient to assist in tilting the plate 30 from the dot-and-dash line position of Figure 2 to the solid position of Figure 2 when the line 18 presses upwardly against the extension 50. As there indicated, the line 18 fits snugly between the extension 50 and the recess 33 and the weight of the apparatus holds it securely in place. Moreover, the plate 30 will be firmly anchored in proper position by reason of extending through the slots 31 in the skirts. In this position also the weights 27 will adjust themselves depending on the slant of the line, and hold the block or housing in upright position at all times, thereby forming a baffle or shield against passage of rats along the line.

When it is desired to remove the housing from the line, it is necessary to do no more than lift upon the tie-rope 15 and by this means the hous-

ing can be lifted from the line and pulled aboard the ship by means of the tie rope 15.

When it is desired to shift the position of the plate to accommodate a line of different diameter, it is necessary to do no more than tilt the plate to its outermost position outside of the slots 31, then press the plate against turns of the spring 40 until the pin 41 is lifted from the slot 42. After rotating the plate thus freed end for end, the spring 40 will press the pin 41 into the slot 42 in the other position of adjustment. In either position, the extension 50 serves as the means of latching the housing to the line.

In a second form of the invention illustrated in Figures 5 through 8, inclusive, the essentials of a successful rat guard of the type herein disclosed are embodied in a guard so jointed that the baffle or shielding portion which prevents passage of the rats along the mooring line remains at all times in a substantially vertical position regardless of the tilt of the mooring line. As shown, there is provided a member 60 having in general the form of a tunnel provided by sides 61 and 62 and a ridge-like top 63 joining longitudinal edges of the sides. The remaining side or bottom of the member is open for reception of a mooring line 64. Cooperable with the tunnel member is a baffle 65 which in the embodiment shown has a somewhat rectangular form in that there are provided side elements 66 and 67 and a back 68 joining the side elements along one vertical edge of each. The back has a cut-out section 69 in order to permit the baffle to tilt freely with respect to the tunnel member 60.

For attaching the baffle to the tunnel member there is provided a somewhat U-shaped bracket 70 which engages beneath the top of the tunnel member, as best illustrated in Figure 7. The bracket includes arms 71 and 72 which extend through suitable apertures in the top to a position wherein the ends of the arms are adapted to be mounted upon a pivot pin 73. As shown, the pivot pin extends through the side elements 66 and 67 and is there properly secured in place by utilization of washers 74 and 75 and cotter pins 76. By this arrangement the baffle is capable of being tilted freely with respect to the tunnel member. In certain positions of tilt, however, a considerable space will be opened between the back of the baffle and the top of the tunnel member. To close this space there is provided a filler plate 77 anchored by welding or other appropriate means at its line of junction 78 with the top of the tunnel member. The filler plate is made high enough so that it will at all times close any gap or space which might appear between the back of the baffle and the tunnel member throughout the entire range of tilt provided between the tunnel member and the baffle.

In order to latch or lock the device to the mooring line 64 a latch similar to that described in connection with Figures 1 through 4, inclusive, is utilized and operates in precisely the same manner.

In the second form of the device counterweights are also included for holding the device in correct position upon a mooring line regardless of the tilt of the line. In this instance a weighted rod member 80 includes vertical rods 81 and 82 which are joined or bent in a somewhat U shape, with a transverse rod section 83 at the top extending from one vertical rod to the other. The rods 81 and 82 may extend above the tops of the side elements 66 and 67 when the rod member 80 is slid upward. To accommodate the vertical

rods, the side elements and the baffle may be provided with longitudinal recessed portions 84 and 85 in the side elements 66 and 67 respectively. These recessed portions are designed to accommodate a free sliding fit of the vertical rods therein. Plates 87 may be riveted as shown or welded over the recessed portions, if desired, to hold the rods in place or the plates may be secured by spot welding, if preferred. Weights 88 and 89 are located at the bottoms of the vertical rods to provide a sufficient counterweight. Constructed as shown the rod member 80 can be lowered to the position of Figure 5, in which position the transverse rod section 83 will contact the tops of the plates 87, thereby preventing the rod member from sliding off. When the rod member is slid up to the position of Figure 6 the weights strike the bottom of the side elements and the transverse rod section can be used as a handle to lift the device.

In operative position the counterweights are extended as illustrated in Figure 5. The tunnel member 60 overlies the mooring line and assumes the tilt of the line while at the same time the baffle 65 is tilted to a substantially vertical position by action of the counterweights regardless of the tilt of the line or the tunnel member 60. In this position the baffle provides a highly effective shield against the passage of rats in either direction along the line. To pass the baffle the rats would have to climb smooth vertical walls where no claw hold is provided and which is sufficiently high so that no rat could possibly jump the required distance.

Beneath the mooring line there is located the plate 30, previously described in connection with the first form of the invention, which is adapted by utilization of the extension 50 and transverse portion 37 to latch the device upon the mooring line. The plate 30 is free to tilt into and out of engaging positions with the mooring line at all usual angles of tilt of the tunnel member with respect to the baffle.

When devices made in accordance with the second form of the invention are removed from the mooring lines, the weighted rod member 80 may be collapsed to the position shown in Figure 6. This can be done by merely resting the counterweights 89 on some surface and permitting the weight of the guard to slide the baffle and the tunnel down to the supporting surface. The same motion will return the tunnel member and the baffle to the relative positions shown in Figure 6. In collapsed position as there shown the devices may be readily stacked side by side on deck. Ordinarily tie ropes are used and these can most conveniently be fastened upon the transverse rod section 83. The same transverse rod section also provides a convenient handle by means of which the devices may be manipulated.

While the invention herein shown and described is considered to be the most practical and preferred embodiment, it is recognized that departures may be made therefrom within the scope of the invention, which is not to be limited to the details disclosed herein, but is to be accorded the full scope of the claims so as to embrace any and all equivalent devices.

The invention having been herein described, what is claimed and sought to be secured by Letters Patent is:

1. A rat guard for a mooring line comprising a housing adapted to ride on the line, said housing comprising a shield adapted to be located above the line having a breadth not less than the di-

the line engaging member on a horizontal axis extending transversely thereof, and a counter-weight on and adapted to extend below the baffle.

5 5. A rat guard for mooring lines comprising a line-engaging member adapted to rest on a line having a top, sides and an open bottom, a latch assembly comprising an extension and plate pivotally mounted on said line-engaging member, said extension adapted to overlie the line and said plate adapted to underlie the line in latched position, a baffle pivotally mounted on the line-engaging member on a horizontal axis extending transversely thereof, and a counter-weight comprising weighted rod means slidably mounted on the baffle for limited movement between a retracted position and a position extended below the line-engaging member.

20 6. A rat guard for mooring lines comprising a line-engaging member adapted to rest on a line having a top, sides and an open bottom, a latch assembly comprising an extension and plate pivotally mounted on the line-engaging member, said extension adapted to overlie the line and said plate adapted to underlie the line in latched position, a baffle pivotally mounted on the line-engaging member on a horizontal axis extending transversely thereof, said baffle comprising side elements substantially parallel to the sides of said line-engaging member and a back joining the side elements, and a counter-weight slidably mounted on the baffle for limited movement between a retracted position and a position extended below the line-engaging member.

30 7. A rat guard for mooring lines comprising a line-engaging member adapted to rest on a line having a top, side walls and an open bottom, a latch assembly comprising an extension and plate pivotally mounted on one of said side walls, said extension adapted to overlie the line and said plate adapted to underlie the line in latched position, and a baffle pivotally mounted on the top of the line-engaging member on a horizontal axis extending transversely thereof, said baffle comprising side elements substantially parallel to the side walls of said line-engaging member, a back joining the side elements along one longitudinal edge of each, a counterweight comprising parallel rod members slidably mounted on the side elements for limited movement to extended and retracted positions having a weight on each rod member, and a filler plate on said line-engaging member adapted in relative tilted positions of said baffle and said line-engaging member to close the gap therebetween.

40 8. A rat guard for a mooring line comprising a housing having parallel side elements extending above and below and on opposite sides of the line, said side elements being adapted to be positioned immediately adjacent to the line, a connecting wall between opposite side elements at a location above the line and limited in width to the space between said side elements, a transverse shield element between said side elements at a location below the line and pivotally mounted on the housing for movement to and from a position underlying the line, said transverse shield element having a member thereon extending obliquely away from the transverse shield element adapted for initial engagement with the line when the transverse shield element occupies a position removed from the line, said member being adapted to overlie the line when said transverse shield element underlies the line,

10 15 25 30 35 40 45 50 55 60 65 70 75 ameter of a line and skirts along the lower edges at each side adapted to overlie the sides of the line, said skirts having transversely aligned slots therein, a counter-balance secured to the housing and extending below the housing for holding the shield erect and a combined rat shield and latch mounted beneath the first identified shield between the skirts, said combined rat shield and latch comprising a plate adapted to extend transversely relative to the skirts within said slots and below the lower edges thereof, a rod having one portion in pivotal engagement with the plate, another portion pivotally suspended on one of said skirts and still another portion thereof extending between the skirts in a position of potential engagement with the line, one edge of said plate having a recess spaced from the last identified portion of the rod and adapted to fit one size of line and another edge having a recess adapted to be spaced from the last identified portion of the rod and to fit another size of line, said plate being rotatable on said rod to positions presenting one or another of said recesses to the line, and locking means for locking said plate in one or another of said positions comprising one element on the plate and another element on the rod, said elements having alternative positions of engagement respectively in said one or another position of the plate.

2. A rat guard for a mooring line comprising a baffle adapted to overlie the line including longitudinally extending skirts adapted to extend along and below the line, and means for anchoring the baffle to the line comprising a transverse plate, said skirts having slots adapted to receive the plate, said plate having a pivotal mounting on a longitudinal axis on one of said skirts and an edge adapted to underlie the line, an extension on the plate overlying said edge in a position of potential engagement with the line, said extension being spaced from the edge a distance substantially equal to the diameter of the line and adapted together with said edge to confine the line therebetween when the guard is rested thereon.

3. A rat guard for a mooring line comprising a baffle adapted to overlie the line including longitudinally extending skirts adapted to extend along and below the line, and a second baffle adapted to anchor the first baffle to the line comprising a transversely disposed plate, said skirts having slots adapted to receive the second baffle, said plate having a pivotal mounting on a longitudinal axis on one of said skirts and an extension on the second baffle at one edge of the plate spaced from said edge a distance substantially equal to the diameter of the line and adapted together with said edge to engage the line when the guard is rested thereon, said plate having recesses of different sizes respectively in said one edge and in the edge opposite thereto and having a reversible mounting on the extension, said plate having one position in the second baffle wherein one recess is at a position adjacent the extension and a second position wherein the other recess is at a position adjacent the extension.

4. A rat guard for mooring lines comprising a line-engaging member adapted to rest on a line, a latch assembly comprising an extension and plate pivotally mounted on said line-engaging member, said extension adapted to overlie the line and said plate adapted to underlie the line in latched position, a baffle pivotally mounted on

and weight means on the lower part of the housing adapted to maintain the housing in erect position when on the line.

9. A rat guard for a mooring line comprising a jointed housing having a lower portion comprising flat parallel side elements adapted to be positioned immediately adjacent the sides of the line and an upper portion having flat parallel side elements in substantial alignment with the first identified side elements, the upper ends of the lower portion and the lower ends of the upper portion being adapted to overlap, a transverse pivot connection between said portions, a permanent wall between said side elements of the upper portion and a shield movably mounted upon and located between said side elements of the lower portion, said housing having a weighted element thereof at a location below the line greater than the weight of the housing above the line whereby the housing maintains an erect position when on the line.

10. A rat guard for a mooring line comprising a housing having upper and lower portions pivotally secured together, said lower portion being adapted to ride on the line, said upper portion comprising a rat shield adapted to be located above the line and skirts along the lower edges at each side adapted to overlie the sides of the line, a counter-balance for holding the shield erect comprising a portion thereof supported on the housing and weighted means terminating below the housing, a latch having a line-engaging portion adapted to lie across the line and a rotatable connection between the latch and the lower portion of the housing with the axis of said rotatable connection adapted to lie substantially parallel to the line, the connection being located on the latch at a point removed from the line-engaging portion, wherein when the guard is free to drop on the line the weight thereof applied to the connection urges the latch simultaneously against the line and rotationally about the connection to a position of releasable engagement with the line.

11. A rat guard for a mooring line comprising a housing having upper and lower portions, said lower portion being adapted to ride on the line, said upper portion comprising a rat shield adapted to be located above the line and skirts along the lower edges at each side adapted to overlie the sides of the line, a counter-balance for holding the housing erect comprising a portion thereof swingably supported on one portion of the housing and weighted means terminating below the housing, a latch element mounted beneath the shield between the skirts, said latch element having a line-engaging portion adapted to lie across the line and a rotatable connection between the lower portion of the housing and the latch element, the connection being located on the latch element at a point removed from the line-engaging portion and having the axis thereof adapted to lie parallel to the line, wherein when the guard is free to drop on the line the weight thereof applied to the connection urges the latch simultaneously against the line and rotationally about the connection to a position of releasable engagement with the line, and a secondary latch shield operably connected to said latch at a location adapted to underlie the line and cooperable with the line when the latch is in engagement with the line.

12. A rat guard for mooring lines comprising a housing having a breadth not substantially greater than the diameter of the line and adapt-

ed to ride on the line, said housing comprising a shield having a length and height exceeding the breadth thereof, skirts along the lower edges at each side adapted to overlie the sides of the line, a counter-balance for holding the shield erect comprising a portion swingably supported on the shield including weighted means terminating below the skirt, and a combined rat shield and latch mounted at the lower portion of the shield between the skirts, said combined rat shield and latch having a line-engaging portion adapted to lie across the line and a rotatable connection between the lower portion of the housing and the combined rat shield and latch, the connection being located on the combined rat shield and latch at a point removed from the line-engaging portion and having the axis thereof adapted to lie parallel to the line wherein when the guard is free to drop on the line the weight thereof applied to the connection urges the combined rat shield and latch simultaneously against the line and rotationally about the connection to a position of releasable engagement with the line.

13. A rat guard for a mooring line comprising a housing adapted to ride on the line, said housing comprising a shield having a breadth not less than the diameter of the line, a length exceeding the breadth and a height exceeding the length, skirts along the lower edges at each side adapted to overlie the sides of the line, said skirts having transversely aligned slots therein, a gravity counter-balance adapted to hold the shield erect on the line comprising a rod pivotally mounted transversely in the housing above the position of contact of the housing with the line, weighted extensions on the rod adapted to have an operative location below the line, and a combined rat shield and latch mounted in said slots beneath the shield and between the skirts, said combined rat shield and latch having a line-engaging portion adapted to lie across the line and a rotatable connection between the lower portion of the housing and the combined rat shield and latch, the connection being located on the combined rat shield and latch at a point removed from the line-engaging portion, wherein when the guard is free to drop on the line the weight thereof applied to the connection urges the combined rat shield and latch simultaneously against the line and rotationally about the connection to a position of releasable engagement with the line.

14. A rat guard for a mooring line comprising a housing adapted to ride on the line, said housing comprising a shield adapted to be located above the line having a breadth not less than the diameter of a line, skirts along the lower edges at each side adapted to overlie the sides of the line, a counter-balance secured to the housing and extending below the housing for holding the housing erect and a combined secondary rat shield and latch mounted beneath the housing between the skirts, said combined secondary shield and latch comprising a plate extending transversely relative to the skirts, means for mounting the plate having one portion in pivotal engagement with the plate and another portion pivotally suspended on one of the skirts, and an extension on the combined secondary shield and latch adapted to extend between the skirts in a position of potential engagement with the line, one edge of said plate having a line engaging section spaced from the extension by substantially the diameter of the

11

line and adapted to fit one size of line and another edge having a line engaging section adapted to be spaced from the extension and to fit another size of line, said plate being rotatable on said one portion for presenting either line 5 engaging section to the line and a temporary detent means having elements thereof respectively on said one portion and on the plate on opposite sides of said one portion, said plate being shiftable to positions presenting one edge or 10

12

another to the line wherein a corresponding element on the plate is adapted to engage the element on said one portion.
